(57) **CLAIM**

The ornamental design for a building, as shown and described.

DESCRIPTION

1. Building

1.1 : Front

1.2 : Left

1.3 : Right

1.4 : Top

1.5 : Perspective

A building having a substantially symmetrical shape around a central axis; the building comprises a base section at ground level and a top section above the base section; the base section has a lower dimension along a direction transversal to the central axis than the top section.
